F. F. BAHNSEN.

AIR MOISTENING DEVICE.

APPLICATION FILED MAR. 26, 1917.

1,254,189.

Patented Jan. 22, 1918.

UNITED STATES PATENT OFFICE.

FREDERIC F. BAHNSON, OF WINSTON-SALEM, NORTH CAROLINA.

AIR-MOISTENING DEVICE.

1,254,189.

Specification of Letters Patent. Patented Jan. 22, 1918.

Application filed March 26, 1917. Serial No. 157,415.

To all whom it may concern:

Be it known that I, FREDERIC F. BAHNSON, a citizen of the United States, residing at Winston-Salem, in the county of Forsyth 5 and State of North Carolina, have invented certain new and useful Improvements in Air-Moistening Devices, of which the following is a specification.

This invention relates to an attachment to 10 an ordinary hot-air house furnace, whereby the air circulating through the house is suitably mixed with water vapor in order to regulate the humidity of the air in the rooms.

15 It is the object of this invention to effect this result by drawing the hot-air from the top of the furnace into a separate chamber, to which a humidifier is connected, and then return the mixture of air and water vapor to 20 the air chamber of the furnace at a point between the house pipes and the cold air inlet, whence it passes to the house.

It is a further object of the invention to 25 provide means whereby any sound caused by the operation of the humidifying device is prevented from communicating itself throughout the house.

The invention is illustrated in the accompanying drawings, in which—

30 Figure 1 is a perspective view of the device as attached to a house hot-air furnace;

Fig. 2 is a side elevation, partly in section, 35 of the moistening chamber and humidifier showing the connections therebetween and showing in addition means for preliminarily heating the water before it enters the humidifier.

Fig. 3 is a vertical section through the furnace showing the connection of the pipes 40 from the moistening chamber to the hot-air chamber of the furnace.

As illustrated in the drawings the apparatus 45 comprises an ordinary hot-air furnace having the usual fire-box 1, chimney-pipe 2, hot-air chamber 3, cold-air inlet 4, and house pipes 5. Connected to the top of the 50 hot-air chamber 3, is a pipe 6 leading thence to the top of a moistening chamber 7. From each side of the bottom of chamber 7 pipes 8 lead back to the air-chamber 3 of the furnace, and connect therewith at a point substantially midway between the house pipes 5 and the cold-air inlet 4. The moistening 55 chamber 7 is mounted on standards 9 separate from the furnace, and the pipes 6 and

8 have sections 6' and 8', respectively, of a sound-deadening material, preferably asbestos, inserted in them between the furnace and the moistening chamber 7. In the back of the moistening chamber 7 is a suitable 60 orifice 10 in which is positioned a humidifying device. The humidifier is separately mounted on standards 12 and is preferably one in which an electric motor 13 drives a disk 14 to which water is fed by pump 15 65 from a tank 16 and from which the water is thrown by centrifugal force onto blades 17, where it is mechanically atomized and then floats out into the atmosphere in the form of a fine spray or mist. The finely 70 divided water is carried along by the current of hot air either as such or as absorbed vapor and is forced through pipes 8 to the hot-air chamber 3 of the furnace.

The humidifier is connected to the moistening chamber 7 merely by means of a flexible sheet 19 of rubber packing or the like which extends from the back of the humidifier case 17' to the edges of orifice 10 and makes the connection air-tight but at the 80 same time prevents any vibration of the motor being communicated to the rest of the apparatus. The bottom of the moistening chamber 7 is inclined and has a water-sealed drain 21 therein connecting with the tank 85 16. The pump 15 in the tank 16 is driven through a shaft 24 connected with the shaft 25 of the motor 13, and forces water from the tank 16 through pipe 26 to chamber 27 and from there the water flows through pipe 90 28 to the center of the disk 14. Instead of the arrangement shown, the pump may be located above the water level of the tank 95 and may be driven by belt from shaft 25 of motor 13. As shown in Fig. 2, the pipe 26 may be connected with a heating coil 29 situated within the chamber 3 near the top thereof and a pipe 30 may lead from coil 29 to the chamber 27. This provides means whereby the water may be preliminarily 100 heated by the hot air from the furnace before reaching the humidifier. The tank 16 is provided with an inlet pipe 31 which may be connected with a water-supply, the flow of water therethrough being regulated by 105 any suitable means, such as a ball and valve, not shown. The hot air is drawn from the top of the air-chamber 3 through pipe 6 by means of a fan 32 mounted in pipe 6 near its junction with the upper end of chamber 7. 110

The shaft 33 of fan 32 is driven from the shaft 25 of motor 13 by means of a belt 34.

In the operation of the device a natural circulation is set up in the air-chamber 3

6 by the heat effect from the fire-box 1, which circulation causes air to pass into the cold-air pipe 4, up through the air-chamber 3 and out through the house pipes 5. To introduce moisture into the air the humidifier motor

10 13 is started, and with it fan 32 and pump

15 15. The fan 32 draws hot air into pipe 6 and forces it into chamber 7, where it is blown over the finely-divided spray of water thrown off from the humidifier, 15 quickly evaporates it, and carries it along through pipes 8 back to the air-chamber 3, where the moistened air is thoroughly mixed with the rising current of hot air in air-chamber 3. The pipes 8 are introduced into

20 the furnace at a point between the cold-air inlet 4 and the house pipes 5, so that the natural circulation is not appreciably impeded, the moist air being carried along up the chamber and out pipes 5.

25 By suitably adjusting the speed of the fan 32 to the conditions of use it has been found that the house circulation is not affected and yet the relative humidity has been raised from approximately 38 per cent.

30 to 52 per cent. in about half an hour, evaporating above two quarts of water in that time. This makes the room air much more pleasant and healthful. The advantage of

35 the use of a mist of water vapor rather than steam is that the temperature of such vapor is always much less than that of the hot air and, therefore, there is no tendency for the vapor to condense, but when steam is used it is much higher in temperature than

40 the hot air with which it mixes, so that a condensation on colder surfaces is likely to result. Moreover, the heaviness and closeness of the air in a room humidified by steam-jets is very perceptible.

45 The transmission of vibration from the apparatus to the house pipe system is eliminated, first, by the provision of the sound-deadening sections 6' and 8' in the pipes leading from the chamber 7 to the furnace; 50 secondly, by the separate mounting of the chamber 7 and humidifier; and thirdly, by the flexible connection 19 between the humidifier and the chamber 7.

I claim:

55 1. The combination with a hot air furnace, of a humidifier and means for abstracting heated air from the furnace, subjecting it to the action of the humidifier and returning it to the furnace in humidified condition.

60 2. The combination with a hot air furnace, of a humidifier, means for abstracting heated air from the furnace, subjecting it to the action of the humidifier and returning it to the furnace in humidified condition

and means in the path of the humidified air for draining off the moisture held in unstable suspension.

3. The combination with a hot air furnace, of a humidifier, and means for establishing an air circuit independently of the air distributing pipes, said circuit including the hot air casing and the said humidifier. 70

4. The combination with a hot air furnace, of a humidifier, means for establishing an air circuit independently of the air distributing pipes, said circuit including the hot air casing and the said humidifier, and means for controlling the flow of air 80 through said circuit. 75

5. The combination with a hot air furnace, of a humidifier, means for establishing an air circuit independently of the air distributing pipes, said circuit including 85 the hot air casing and the said humidifier, and means for controlling the degree of humidification.

6. The combination with a hot air furnace, of a humidifier, means for establishing 90 an air circuit independently of the air distributing pipes, said circuit including the hot air casing and the said humidifier, and means in the said circuit for preliminarily heating the feed-water for said humidifier. 95

7. A device for moistening air comprising a hot-air furnace, a hot-air circuit connected therewith comprising the hot-air chamber of the furnace, a moistening chamber apart from the furnace, pipe connections leading to and from the air-chamber and the moistening chamber, means for causing a circulation of hot air through said circuit parallel to the natural hot-air circuit through the furnace, and means in said moistening chamber for introducing a mist of water into the path of the hot air. 100

8. A device for moistening air comprising 110 a hot-air furnace, a hot-air circuit connected therewith comprising the hot-air chamber of the furnace, a moistening chamber apart from the furnace, pipe connections leading to and from the air-chamber and the moistening chamber, means for causing a circulation of hot air through said circuit parallel to the natural hot-air circuit through the furnace, means in said moistening chamber for mechanically producing a mist of water in the path of the hot air, and means for preliminarily heating the water before it is transformed into mist. 115

9. A device for moistening air comprising 125 a furnace having a hot-air chamber, a cold-air inlet at the bottom of said air chamber, hot-air outlet at the top of said air-chamber, a moistening chamber, a pipe connection from the top of said air chamber to 130

said moistening chamber, pipe connections from the moistening chamber to the air-chamber, said pipes entering said air-chamber at a point between the cold air inlet 5 and the hot-air outlet, means in said pipes for causing a circulation of hot air therethrough from the top of the air-chamber, and means in said moistening chamber for mechanically producing a mist of water in 10 the path of the hot air.

10. A device for moistening air comprising a hot-air furnace, a moistening chamber spaced apart therefrom and having an 15 opening in one face thereof, pipe connections between the furnace and the moisten-

ing chamber, sections of sound-deadening material in said pipe connections, a humidifier projecting into an orifice in said moistening chamber, but spaced therefrom, said humidifier and moistening chamber being 20 separately mounted from each other and the furnace, and a flexible packing between the humidifier and the moistening chamber to close the connection therebetween.

In testimony whereof I affix my signature 25 in presence of two witnesses.
